VEHICLE DRYER ARCH

Earl Dallas Smith, 6202 E. Sage Drive, Scottsdale, Ariz.
85251, and Dale R. Oldham, 7028 N. 11th St., Phoenix,
Ariz. 85034

Filed Dec. 18, 1967, Ser. No. 9,819

Term of patent 14 years

(Cl. D49—12)

Fig. 1

Fig. 2

Fig. 3

Fig. 4

Fig. 5

FIG. 1 is a front elevational view of a vehicle dryer arch showing our new design.

FIG. 2 is a rear elevational view thereof.

FIG. 3 is a top plan view thereof.

FIG. 4 is a right-hand side elevational view thereof.

FIG. 5 is a sectional view at line 5—5 in FIG. 2 and viewed in the direction of the arrows.

The left-hand side is a mirror image of the right-hand side shown in FIG. 4.

We claim:

The ornamental design for a vehicle dryer arch, substantially as shown and described.
